Attorney.

UNITED STATES PATENT OFFICE.

NEIL CURRIE, OF DALLAS, TEXAS, ASSIGNOR OF ONE-FOURTH TO C. L. WARREN, OF DALLAS, TEXAS, AND ONE-FOURTH TO DAN DAVIES, OF ST. LOUIS, MISSOURI.

WATCH.

No. 848,976.

Specification of Letters Patent.

Patented April 2, 1907.

Application filed February 27, 1905. Serial No. 247,568.

To all whom it may concern:

Be it known that I, NEIL CURRIE, a citizen of the United States, residing at Dallas, Texas, have invented certain new and useful 5 Improvements in Watches, of which the following is a specification.

My invention relates to watches, and more particularly to certain features of the movement of watches; and the object is to provide a construction or arrangement by which the mainspring of the watch can be taken out or put in without either taking the watch apart or removing the watch-movement from the casing and to produce watches which will 15 be more simple in construction and which can be manufactured at smaller cost and which will give better results.

One of the advantages is that the mainspring can be put in by simply unscrewing one screw 20 and without removing the movement from the case.

Another advantage is that the mainspring-barrel is located partly in the mainspring-barrel plate or top plate, thus making it possible 25 to make a deeper barrel in which a wider spring can be used, and the winding or ratchet wheel can be placed above the top plate. The watch can with this arrangement be made thinner and yet have a wider mainspring.

30 Other objects and advantages will be fully explained in the following description, and the invention will be more particularly pointed out in the claims.

Reference is had to the accompanying 35 drawings, which form a part of this application and specification.

Figure 1 is a plan view of sufficient parts of a watch to illustrate my invention. Fig. 2 is 40 a side elevation of the same. Fig. 3 is a vertical section along the line $x-x$ of Fig. 1.

Similar characters of reference are used to indicate the same parts throughout the several views.

This improvement is applicable to any 45 watch or clock of ordinary construction. In the drawings the top plate A is secured to the main plate G by the pillars R and screws r. The mainspring-barrel C is mounted in a recess turned out in the plate A, and the ratchet 50 wheel B is made integral with the barrel C. The barrel C is held in place partly by being located in a recess turned out in the plate A and mainly by the combined pillar, arbor, screw D. The lower end of the screw D is reduced and threaded and screwed into 55 the main plate G. The main drive-wheel H

of the watch-movement is mounted on the arbor D and meshes with a pinion J, which is mounted on the arbor c, which has the upper end journaled in the top plate A. The wheel 60 E is mounted also on the arbor c and is thus driven by the drive-wheel H. The hub of the drive-wheel H has a sleeve F extending upward, and the barrel C has a downwardly-projecting bearing b, which rests on the sleeve 65 F. Friction can be reduced by making the bearing b and the sleeve F thin. As a pillar the element D holds the barrel and ratchet-wheel B against vertical movement. The element D being screwed into the plate G secures 70 all the elements, the wheel H with the sleeve F, and barrel C in place, and the ratchet-wheel B being integral with the barrel C is also held in place by the element D. The mainspring K may be secured to the barrel 75 C and to the wheel H in the usual manner.

Having fully described my invention, what I claim as new, and desire to secure by Letters Patent, is—

1. A watch having top and bottom plates, 80 a mainspring-barrel having a ratchet-wheel formed integral therewith, said barrel being mounted in and projecting through a recess turned out in said top plate and said wheel being located above said top plate, and a 85 combined arbor and screw coöperating with said top plate for holding said barrel in position.

2. In a watch provided with top and main plates, a mainspring-barrel mounted in and projecting through a recess turned out in said top plate and having a winding or ratchet wheel formed integral therewith and located above said top plate, and a combined arbor and screw for holding said barrel in position, 95 said barrel having a sleeve engaging said arbor.

3. In a watch provided with top and main plates, a mainspring-barrel mounted in and extending through a recess turned out in said top plate and having a ratchet-wheel formed integral therewith and located above said top plate, a combined arbor and screw for said barrel secured in said main plate, a main drive-wheel mounted on said arbor and having 100 a sleeve projecting upward about said arbor, and a bearing integral with said barrel and resting on said sleeve.

4. In a watch provided with a top plate and a main or bottom plate and a main drive-wheel; a combined arbor and screw secured 110 in said bottom plate, said main drive-wheel

being mounted on said arbor and having an upwardly-extending sleeve, and a main-spring-barrel having a ratchet-wheel formed integral therewith and having a bearing projecting downward and resting on said sleeve, said barrel being supported in a recess formed in said top plate and said ratchet-wheel being located above said top plate.

In testimony whereof I set my hand, in the presence of two witnesses, this 9th day of 10 February, 1905.

NEIL CURRIE.
